CASE AND MOVEMENT FRAME FOR
WATCHES AND THE LIKEElof L. Carlson, Bristol, Conn., assignor to The
E. Ingraham Company, Bristol, Conn., a cor-
poration of Connecticut

Application February 23, 1939, Serial No. 257,916

3 Claims. (Cl. 58—88)

The present invention relates to improvements in case and movement-frame constructions for watches and instruments of similar character having running parts mounted in rigidly-spaced front and back movement-plates within a closed casing.

The general object of this invention is to provide an improved case and movement-frame construction by means of which the thickness of a watch or other instrument of similar character may be reduced without changing the essential character or arrangement of the running parts therein.

One object of the invention is to provide an improved construction and arrangement of parts in a watchcase and the movement frame encased therein by means of which a watch-movement or the like without reconstruction or rearrangement of its running parts, may be encased in a watch-case of less axial depth than that heretofore considered necessary for the purpose.

Ancillary to the foregoing objects, the present invention has for its objectives: an improved construction for either or both of the movement-plates which support the running parts of the watch-movement; and a more compact arrangement of the watch-movement within the watchcase and thereby rendering it possible to reduce the axial depth of the latter.

Another object of the invention is to provide an improved construction for either or both of the said movement-plates by means of which the peripheral flange or radially-projecting lugs or the like, by means of which the front and back movement-plates are rigidly connected to interposed pillars, may be arranged in closer axial relationship than the central portions of said movement-plates between which most of the running parts of the watch-movement are arranged.

A specific object of the present invention is to provide an improved movement-frame construction which will enable a watch-movement of inexpensive type to be mounted in a watch case of smaller size than heretofore required for the purpose without the necessity of making any changes in design of the watch-movement itself.

Still another object of the invention to which the foregoing object is ancillary, is to enhance the appearance and "eye appeal" of a watch of inexpensive type; to adapt it to occupy less space; and to facilitate its deposit in and removal from a pocket or other receptacle.

With the above and other objects in view, as will appear to those skilled in the art from the

present disclosure, this invention includes all features in the said disclosure which are novel over the prior art.

In the accompanying drawings, in which one mode of carrying out the present invention is shown for illustrative purposes:

Fig. 1 is a front elevational view of a watch embodying the present invention;

Fig. 2 is an edgewise view of the same as seen from the right of Fig. 1;

Fig. 3 is an enlarged axial sectional view of the same taken on the line 3—3 of Fig. 1;

Fig. 4 is a view in rear elevation of the watch-movement removed from its case;

Fig. 5 is an edgewise view of the movement-frame as it would appear from the top of Fig. 4, with the running parts of the watch-movement removed;

Fig. 6 is a rear view in perspective of the back movement-plate detached;

Fig. 7 is an edgewise view similar to Fig. 5 of a modified form of the movement-frame; and

Fig. 8 is a rear view in perspective on a reduced scale of the back movement-plate shown in Fig. 7.

For the purpose of encasing a watch-movement of established form, without reconstruction or rearrangement of its operating parts, within a watchcase of smaller axial depth than that usually considered essential for the purpose, the present invention contemplates the use of a center-band of smaller axial depth than has heretofore been considered necessary. In this way, the back-plate of the watchcase and the bezel therefor, with its included crystal, are brought into closer axial relationship than has heretofore been done in certain types of watchcases. For this purpose, according to the present invention, the axial depth of those portions of the front and back movement-plates of the movement frame extending around and within the center-band, are displaced axially with respect to each other into closer relationship than that existing between the central portions of the front and back movement-plates, between which most of the running parts of a watch-movement or the like are usually accommodated.

For this purpose, again, the axial length of the pillars interposed between the front and back movement-plates is materially shortened without reducing the axial depth of the space intervening between the central portions of the movement-plates.

The particular movement frame and watch-case chosen for the illustration of the present invention in Figs. 1 to 6 inclusive, includes a move-

ment frame generally designated by the reference character 10 and a watchcase, comprising: a center-band generally designated by the reference character 11; a back-plate 12 of the watchcase; a bezel 13; and a crystal 14. As shown particularly well in Figs. 5 and 6, the movement frame 10 comprises a front movement-plate 15, a back movement-plate generally designated by the reference character 16, and pillars 17 which are riveted at their forward ends 18 to the front-plate 15 and rigidly connected at their rear ends to the back movement-plate 16 by means of screws 19. The said pillars 17, of which there are preferably four arranged in spaced-apart relation about the periphery of the movement frame 10, are provided with movement-retaining shoulders 20 by means of which the watch-movement is retained in position within the watchcase in the usual manner.

20 The back movement-plate 16 comprises a central body-portion 21 and a peripheral connection-flange 22 which is provided with holes 23 through which the screws 19 are threaded into the adjacent ends of the spacing-pillars 17. As shown in the drawings, the connection-flange 22 is offset axially with respect to the central body-portion 21 of the back movement-plate 16 and inasmuch as the central body-portion 21 of the said back movement-plate is spaced from the central portion 30 of the front movement-plate 15 at an axial distance substantially equal to that at which the front and back movement-plates are usually spaced for watch-movements of the character illustrated, the axial space intervening between 35 the connecting-flange 22 and the front movement-plate 15 is less than that which usually intervenes between the front and back movement-plates in watch-movements of this character.

As clearly shown in Fig. 3, when the watch-movement is placed within the center-band 11 of the watchcase, the front movement-plate 15 is arranged with its outer peripheral edge in lateral abutment with segmental flanges 24. Preferably, the segmental flanges 24 correspond in number to 45 the number of spacing-pillars 17, of which, as described and shown, there are four, and the said segmental flanges are arranged with respect to the center-band 11 in spaced-apart relation substantially similar to the spaced-apart relation of 50 the pillars 17 with respect to the movement frame 10. The segmental flanges 24 project radially inward from a circular snap-flange 25 to which the bezel 13 of the watchcase is attached in the usual manner and they also project axially in a rearward direction from the front snap flange. In placing the watch-movement 10 within the center-band 11, as mentioned, the former may, for example, be positioned with the shoulders 20 of the four pillars 17 each disposed to pass 55 one of the segmental flanges 24 and, thereafter, the watch-movement 10 may be turned within the center-band 11 to bring the shoulders 20 of the said spacing-pillars 17 beneath the segmental flanges 24. When thus positioned, the segmental flanges 24 are interlocked between the front movement-plate 15 and the movement-retaining shoulders 20 on the pillars 17. In consequence, the offset connection-flange 22 of the back movement-plate 16 is disposed within and adjacent to the inner periphery of a snap-ring or flange 26 at the rear edge of the center-band 11, while the central body-portion 21 of the said movement-plate is arranged to protrude axially beyond the rear edge of the said center-band 11 and into closer proximity to the back-plate 12 of the

watchcase than it does in present well-known constructions in which the back movement-plate has its connection-flange and central body-portion arranged in a common plane.

It will be understood from the foregoing that by axially displacing the peripheral connection-flange 22 towards the front movement-plate 15, to which it is rigidly attached by means of interposed pillars 17 of shorter length than those usually employed, it becomes possible to construct the center-band 11 of less axial depth than heretofore and thus to arrange the bezel 13 and back-plate 12 of the watchcase in closer axial relation to each other than has heretofore been possible in watchcase and movement-frame constructions of the character illustrated without reducing the space intervening between the front and back movement-plates. In this way, the thickness of a watch may be materially reduced without the necessity for a reconstruction and rearrangement of the running parts of the watch-movement. The back-plate 12 of the watchcase is provided with a peripheral snap-groove 27 by means of which it is attached to the outer periphery of the snap-ring 26.

For the purpose of more clearly illustrating the essential features of the present invention, all of the running parts of the watch-movement are not illustrated on the drawings. The watch-movement is represented by the following parts.

A spring-barrel 28 carries a main-wheel 29 mounted on the main arbor 30. Meshing with the main-wheel 29 is a first pinion 31 carried by a center-arbor 32. A second or minute-wheel 33 moving with the first pinion 31, is in mesh with a second pinion 34 on its arbor 35. A third wheel 36 on arbor 35 meshes with and drives a third pinion 37. Interposed between the first pinion 31 and a shoulder on the center-arbor 32 is a center-friction 39, the said center-arbor 40 having secured thereto a cannon-pinion 38. Concentrically arranged with the center-arbor 32 on the inner side of a dial-plate 40 is an hour-wheel 41 to which is connected an hour-hand 42. Mounted on the front end of center-arbor 32 is a minute-hand 43. As shown in Figs. 1 and 2, the center-band 11 of the watchcase carries a pendant-head 44 to which is connected a pendant-ring 45.

According to the embodied form of the movement frame shown in Figs. 7 and 8, the said movement frame comprises a front movement-plate 46, a back movement-plate generally designated by the reference character 47, and pillars 48 interposed between the said movement-plates. Arranged around the outer periphery of the back movement-plate 47 are a plurality of connection-lugs or portions 49 which may be integrally formed therewith or connected thereto in any suitable manner, such, for example, as by brazing. The connection-lugs 49 are provided with holes 50 through which screws 51 may be threaded into the adjacent ends of the pillars 48, the other ends of said pillars 48 being riveted at 52 in rigid engagement with the front movement-plate 46. The pillars 48 are provided with movement-retaining shoulders 53 suitably arranged adjacent the front movement-plate 46 to provide an interlocking connection between the movement frame and the segmental flanges 24 arranged around the front edge of the center-band 11. It will be understood that the arrangement of connection-lugs 49 to project radially from the periphery of the back movement-plate 47 at the inner surface thereof, serves to reduce

the axial depth of the space intervening between the connection-portions of the front and back movement-plates 46 and 47 in a manner substantially similar to that described above by 5 means of the offset connection-flange 22 with respect to the central body-portion 21 of the back movement-plate 46 and in relation to the front movement-plate 45. According to Figs. 7 and 8, pillars 48 of foreshortened length are interposed between the connection-lugs 49 and the front movement-plate 46 to provide a movement frame which is reduced in axial depth around its periphery. As thus constructed, the movement frame, with its included movement, may be 10 mounted in a center-band of foreshortened axial depth, to effect an arrangement of the bezel and back-plate of the watchcase in closer axial relation to each other than has heretofore been considered feasible in certain types of watches without costly changes being made in the design and 15 arrangement of parts in the watch-movement.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended 20 to be embraced therein.

I claim:

1. In a watch, the combination with a center-band provided with front and rear snap-flanges; a front movement-plate smaller in diameter than 25 the inner diameter of the said front snap-flange and encircled thereby substantially in a common plane therewith; a rear movement-plate smaller in outside diameter than the inner diameter of the rear snap-flange and having a connection-flange disposed substantially in a common plane with and encircled by the rear snap-flange, the central body-portion of the rear movement-plate being rearwardly offset from the said connection-flange to provide a watch-movement-accommodating space substantially equivalent to that provided between front and rear movement-plates without axially-offset portions, and similarly-arranged with respect to a center-band having 30 front and rear snap-flanges; spacing-pillars rigidly interposed between the said front movement-plate and the said connection-flange of the

rear movement-plate; and means for releasably connecting the said front movement-plate to the said front snap-flange.

2. In a watch, the combination with a center-band provided with front and rear snap-flanges; peripherally-spaced segmental-flanges presented inwardly from the inner periphery of the front snap-flange; a front movement-plate having an outside diameter smaller than the inner diameter of the front snap-flange and in axial abutment 10 with the said spaced segmental-flanges; a rear movement-plate having an outside diameter smaller than the inner diameter of the rear snap-flange, the said rear movement-plate comprising a central body-portion disposed at an axial distance from the front movement-plate greater than the axial spacing of the said snap-flanges and a connection-flange offset forwardly therefrom and disposed substantially in a common transverse plane with the rear snap-flange; and 15 spacing-pillars rigidly interposed between the front and rear movement-plates and in interlocking engagement with the said segmental-flanges.

3. In a watch, the combination with a center-band provided with front and rear snap-flanges; peripherally-spaced segmental flanges presented inwardly from the inner periphery of the front snap-flange and axially offset therefrom in a rearward direction; a front movement-plate 25 smaller in diameter than the inner diameter of the front snap-flange and disposed substantially in a common plane therewith and in axial abutment with the said segmental flanges within the said inner periphery of the front snap-flange; a rear movement-plate smaller in outside diameter than the inner diameter of the front snap-flange and having a connection-flange disposed substantially in a common plane with the rear snap-flange, and a central body-portion disposed at 30 an axial distance from the front movement-plate greater than the axial spacing of the said snap-flanges; and spacing-pillars rigidly interposed between the front movement-plate and the connection-flange of the rear movement-plate to retain the said movement-plates in assembled relation to each other and having an interlocking engagement with the said segmental flanges at 35 the front snap-flange.

ELOF L. CARLSON. 50
